(57) CLAIM

We claim the ornamental design for an embossed container, as shown and described.

DESCRIPTION

FIG. 1 is a top perspective view of an embossed container according to the first embodiment;

FIG. 2 is a front view of FIG. 1;

FIG. 3 is a top perspective view of the embossed container according to a second embodiment; and,

FIG. 4 is a front view of FIG. 3.

The ornamental design which is claimed is shown in solid lines in the drawings. The evenly-sized broken lines consisting of dash-dot lines depict portions of the embossed container that form no part of the claimed design.

1 Claim, 4 Drawing Sheets
